UNITED STATES PATENT OFFICE.

ANDREW NELSON, OF CHICAGO, ILLINOIS.

CONVERTIBLE BENCH.

1,147,537.

Specification of Letters Patent. Patented July 20, 1915.

Application filed May 10, 1913. Serial No. 766,893.

To all whom it may concern:

Be it known that I, ANDREW NELSON, a citizen of the United States, and a resident of the city of Chicago, county of Cook, and 5 State of Illinois, have invented certain new and useful Improvements in Convertible Benches, of which the following is a specification.

My invention relates to convertible benches 10 and more particularly to a device adapted for use as a bench when closed and for use as a bed or couch when extended.

The object of my improvement is to provide a device of the character mentioned 15 which will be simple of construction and efficient in operation.

Other objects will appear hereinafter.

The invention consists in the combinations and arrangements of parts hereinafter 20 described and claimed.

The invention will be best understood by reference to the accompanying drawings forming a part of this specification, and in which,

25 Figure 1 is a plan view of a bench embodying my invention, and having the seat portion opened, Fig. 2 is an enlarged section of the same with the seat closed, Fig. 3 is an enlarged fragmental view of a portion of 30 the corner of the construction in extended position, Fig. 4 is a view of the device in extended position, Fig. 5 is a longitudinal section of the same, and Fig. 6 is a side view of the portion shown in Fig. 3.

35 The preferred form of construction as illustrated in the accompanying drawings comprises a frame made up of four corner posts 7 which are connected in pairs by means of end portions 8. From two of the 40 corner posts 7 are rigidly secured portions 9 which connect the remaining posts 7 completing the frame proper when the device is folded. Hingedly secured to each of the side rails 9 is connected a foldable side member 10, connected as at 11. Connecting each of the members 10 and the next corner post 7 are foldable members 12, secured to the members 10 and posts 7 by means of hinges 13. The portions 10 and 12 are adapted to 50 be folded inside the frame when the device is closed and extended to form the side rails of the device when in extended condition. Pivotally secured to each of the members 10 is a spacing bar 14 and the same are provided with a connection by which their free 55 ends are secured together to rigidly space

the side rails of the device apart when in extended position. The connection between the members 14 comprises a slot 15 in one member 14 and a thumb bolt 16 in the other 60 of said members. To connect the members the slot 15 is engaged by the thumb 16 to rigidly lock the bars 14 in position. On the inside of members 10 and 12 opposite one of the hinges 13 are locking buttons 17 adapted 65 to give further rigidity to the points between members 10 and 12 when the device is in extended position. A seat portion 18 is hinged to two of the corner posts 7 by means of hinges 19 and adapted to form a seat portion 70 for the device when it is closed and for a pillow support when the device is opened. The pivotal movement of the member 18 on hinges 19 is limited by a stop 20 to maintain it in a position such as indicated in Figs. 4 75 and 5.

Secured to one of the end rails 8 is a flexible sheet of material 21, preferably formed of canvas. The sheet 21 is secured to the end rail 8 by means of a bar 22 securing the 80 end of the sheet 21 substantially as indicated in Figs. 2 and 5. The other end of the flexible sheet 21 is provided with a loop in which is mounted a bar 23. At each end of the bar 23 is hinged an arm 24, as at 25, 85 and each of the arms 24 is provided with a pin 26 adapted to engage a socket 27 the latter being secured to said side rails. Stop members 28 are provided on the frame of the device in suitable positions to engage the 90 free ends of the bar 23 to limit its downward movement, substantially as indicated in Figs. 3, 4, 5 and 6.

Locking bars 29 are pivoted to the under sides of end rails 8 as at 30 and buttons 31 95 provided on said members 8 substantially in the positions indicated in Figs. 1 and 2 to lock the lower sides of the frame of the device when the device is in closed condition. The device is further locked when in this 100 condition by means of locking links 32 which are pivotally connected to the members 10. Buttons 33 are provided on the members 12 to engage suitable slots in the links 32 to effectively lock the upper sides of the portions of the frame thus locking the frame in a rigid body. The locking bars 29 further 105 serve the purpose of supporting the flexible member 21 when rolled or folded in the closed condition of the device.

Secured along the side edges of the flexible member 21 are ears 34. The side members

10 and 12 are provided with buttons 35 adapted to engage the free ends of the ears 34 and effect lateral stretching of the flexible member 21.

5 In operation, the device is unfolded by moving the members 10 and 12 from the positions indicated in Fig. 1 to those indicated in Fig. 4, by moving them on their pivotal connections. The members 14 are 10 then locked substantially in the positions indicated in Fig. 4 to rigidly space the side rails of the device apart. The buttons 17 are locked to give greater rigidity to the frame. The flexible member 21 is unrolled and the 15 arms 24 swung on their pivotal points until the pins 26 engage sockets 27 when the bar 23 is pressed downwardly until it engages the stops 28 thereby effectively locking the bar 23 in its mounting substantially as indicated in Figs. 4, 5 and 6. The ears 34 are 20 engaged on the buttons 35 to stretch the flexible sheet 21 taut laterally. The device is folded in a similar manner to that already explained for opening it; as will be readily 25 understood.

While I have illustrated and described the preferred form of construction for carrying my invention into effect, this is capable of variation and modification without departing 30 from the spirit of the invention. I, therefore, do not wish to be limited to the precise details of construction set forth, but desire to avail myself of such variations and modifications as come within the scope of 35 the appended claims.

Having described my invention what I claim as new and desire to secure by Letters Patent is:

1. A device of the class described, comprising a pair of transverse end members 40 and a pair of side members, each of said side members comprising a plurality of foldably connected sections, in combination with a flexible sheet, one end of said sheet being 45 fixedly secured to one of said end members, a roller bar secured to the other end of said

sheet, sockets in the side members to receive the ends of said roller bar, and coöoperating means on said roller bar and said side members for maintaining the ends of said bar 50 within said sockets, substantially as described.

2. A device of the class described, comprising a pair of transverse end members and a pair of side members, each of said side 55 members comprising a plurality of foldably connected sections, in combination with a flexible sheet, one end of said sheet being fixedly secured to one of said end members, a roller bar secured to the other end of said 60 sheet, sockets in the side members to receive the ends of said roller bar, arms hinged to said bar adjacent the ends thereof, laterally projecting pins on the ends of said arms and sockets fixed to said side members above 65 the level of the first mentioned sockets and toward the opposite end of the device to receive said pins, substantially as described.

3. In a device of the class described, the combination of a frame having rigid end 70 portions and foldable side portions, the latter comprising members pivotally connected, catches locking said pivotal members against pivotal movement, a sheet of flexible material secured to one of said rigid end portions, a bar carried by the other end of said 75 flexible material, arms carried at the ends of said bar, socket members on the inner sides of said side portions, pins on the free ends of said arms detachably engaging said 80 socket members, and supporting stops on said side portions limiting the downward swinging of said arms, substantially as described.

In testimony whereof I have signed my 8. name to this specification in the presence of two subscribing witnesses.

ANDREW NELSON.

Witnesses:
